JIGGER

Filed Dec. 1, 1921

UNITED STATES PATENT OFFICE.

WILLIAM JOSEPH LYNCH, OF GYMPIE, QUEENSLAND, AUSTRALIA.

JIGGER.

Application filed December 1, 1921. Serial No. 519,250.

To all whom it may concern:

Be it known that I, WILLIAM JOSEPH LYNCH, subject of the King of Great Britain, residing at Gympie, Queensland, Australia, have invented certain new and useful Improvements in Jiggers, of which the following is a specification.

This invention relates to an improved jigger for use in separating ore particles from stone particles or gangue in an efficient and expeditious manner.

In carrying out my invention I provide two hutches, or perhaps in some cases a single hutch, having sloping bottoms and the usual outlets. Suspended in these hutches from rockers pivoted above is a pair of jigger boxes fitted with screens or sieves. Intermittent vertical movement is imparted to the jigger boxes by any suitable means. The hutches are each divided into two compartments and outlet shoots on the ends of the jigger boxes deliver the stone particles or gangue into one compartment, while the ore particles are delivered through the screens or sieves into the other compartment. The ore and stone particles are delivered from the respective compartments as and where desired.

In order that my invention may be better understood I will now describe it with the aid of the accompanying drawings, in which—

Fig. 1 is an end elevation (part in section).

Fig. 2 is a side elevation (part in section).

In carrying out my invention I construct a pair of hutches A, carried by a frame B and having sloping bottoms A¹. Outlets A² A³ lead as and to where desired. I may in some cases use single hutches.

Pivoted carried by the frame B are rocking beams C which in turn pivotally carry the two pairs of yokes D. The rocking shaft C¹ which carries the rocking beams C may be pivoted as shown in the drawings or the pivots C² may be carried by the side members of the frame B.

From these yokes D jigger boxes E are suspended as by rods E¹ or otherwise, stretching screws E² or other means being provided so that the level of the boxes E may be properly adjusted. The jigger boxes E are fitted with the usual screens or sieves and each have at one end an outlet E³, ad-

justable as to height. I prefer that the jigger boxes E should be arranged in pairs so that the one counterbalances the other, although it is possible that a single box may be arranged: in which cases the rocking beams C would be suitably balanced.

The hutches A are fitted with partitions F just beyond the end of the jigger boxes E which divide it into two compartments F¹ F² and the outlets E³ from the boxes E slope down over the tops of these partitions F.

Motion is imparted to the jigger boxes E by means of the eccentric H, driven from any source of power supply, eccentric rod H¹, slide rod H² and lever H³ carried by the rocking beams C. Movement of the lever H³ on the slide rod H² is provided between the collars, shoulders or nuts H⁴ which may be adjusted as desired, so that intermittent action is given to the rocking beams C.

In constructing jiggers according to our invention we would vary the constructional details as found desirable, the material used being that best suited for its purpose.

The operation of my invention is as follows:—The eccentric H having been set in motion, the collars, shoulders or nuts H⁴ on the slide rod H² operate on the lever H³ thus rocking the rocking beam C. An up and down movement is imparted to the jigger boxes E and as intermittent movement is given to the lever H³ by the slide rod H² a jerky action is given to the jiggers E. The ore particles fall through the sieve or screens in the bottom of the jigger boxes E into the compartment F¹ of the hutch A and the stone particles or gangue passes out over the outlets E³ into the compartment F².

Having now fully described and ascertained my said invention and the manner in which it is to be performed, I declare that what I claim is—

1. A jigger including a frame, a plurality of hutches supported by the frame, a partition arranged in each hutch and dividing the interior of the hutch into two compartments, a box arranged in each hutch and adapted to discharge ore into one of said compartments of the hutch in which the box is arranged, a chute for each box adapted to discharge stones and gangue into the other compartment of the hutch in which the box is arranged, extensible rods supporting each of said boxes, yokes connected

to said rods, a rocking beam carrying said yokes, and means for rocking said beam and jarring said boxes.

2. A jigger as claimed in claim 1 in which the last mentioned means includes a slotted post connected to said beam, a bar extending through the slot of the post, abutment members arranged in spaced relation on the bar and adapted to alternately contact with the post, and means for reciprocating said bar.

3. A jigger including a plurality of parallel hutches, each provided with a transverse partition dividing the same into a plurality of compartments, outlets for each of said compartments, a frame extending above said hutches, a rocking beam pivotally mounted intermediate its ends on said frame, yokes pivotally connected interme-

diate their ends to the ends of the rocking beam, links connected to the outer ends of the yokes, jigger boxes connected to said links, arranged in said hutches and adapted to discharge ore through their bottoms into one compartment of each hutch, a chute carried by the box and adapted to discharge stones and gangue into the other compartment of the same hutch, a post extending from the rocking beam and having an aperture, a reciprocating link extending through said aperture and having spaced abutments adapted to intermittently strike the post when the last mentioned link is reciprocated, and means for reciprocating the last mentioned link.

In testimony whereof I affix my signature.

WILLIAM JOSEPH LYNCH.
